UNITED STATES PATENT OFFICE.

WILLIAM J. O'GORMAN, OF NEW YORK, N. Y.

SPARK-PLUG.

1,228,958.

Specification of Letters Patent. Patented June 5, 1917.

Application filed June 14, 1916. Serial No. 103,651.

To all whom it may concern:

Be it known that I, WILLIAM J. O'GORMAN, a citizen of the United States, and a resident of New York, in the county of New York and State of New York, have invented certain new and useful Improvements in Spark-Plugs, of which the following is a specification.

My invention relates to the construction of spark plugs for internal combustion engines.

Among other things the object of my invention is to increase the strength of the spark at ignition points of the plug, to provide a plug with a reserve ignition gap which shall come automatically into action in case the plug fails to function properly at the main spark gap, to provide a supplemental gap which may be used as an emergency gap and function in the ordinary way of a spark plug in case the remaining gaps become ineffective, to provide means whereby it may be ascertained by visual inspection whether the plug is functioning properly at the ignition gap and to obtain other advantages which will be apparent to those skilled in the art from the subjoined description.

To these ends my invention consists in the features of construction and combinations of parts hereinafter described and claimed.

In the accompanying drawings Figure 1 is a vertical central section through one form of plug embodying my invention.

Fig. 2 is a side elevation of said plug.

Fig. 3 is an elevation taken at right angles to Fig. 2.

Fig. 4 is an elevation of the core or insulation removed from the metal shell.

Fig. 5 is a view of a detail of the construction.

Referring to the accompanying drawings, 1 indicates the insulating body of porcelain or other suitable insulating material forming the body of the spark plug and carrying 45 in the present instance two wires or connections numbered 3, 4 respectively. 2 indicates the metal body or shell of the plug furnished with the usual screw thread at 5 for attachment of the plug to the engine. 50 The insulated wires or rods 4, 3 terminate respectively at one end in the points 6, 7 to constitute the ignition spark gap of the plug. At their other end said wires or rods 4, 3 terminate respectively in points 8, 9 55 which, in conjunction respectively with the

points 10, 11, constitute artificial spark gaps located in the circuit of the ignition gap at opposite sides thereof respectively. The points forming the artificial gaps are preferably seated or supported in the porcelain or other insulating body itself and in chambers therein furnished with openings through which the sparks of said ignition gaps may be seen. Said openings may be formed in the sides or top of the plug or in both as desired and may be closed either by wire gauze 30 as indicated at one side in Fig. 2 or by translucent material which, if desired, is made as a lens 40 so as to magnify the size of the spark as observed.

The wire gauze is preferably set in a frame 35 which may be forced into the opening or withdrawn therefrom for cleaning so that the spark may be at all times readily seen through the gauze and in the case of 75 the glass or lens said lens may be set permanently in the porcelain.

The points 10, 11 are preferably formed at the terminals of adjustable screws 12, 13 whereby the size of the artificial gap may 80 be regulated and suitable clamping nuts or binding devices are provided on said screws, as indicated, for attachment of the leading wire 15 and for a return wire or connection 16, the latter in the present instance being 85 used as a ground wire grounded through the metal of the engine by attachment of it to a binding post or screw 17 which is mounted on the metal body or shell of the plug. In addition to the ignition points or gaps described, I provide reserve points formed by a wire or terminal 18 permanently attached to the metal body and adapted to co-operate with a point 19 to form an ignition gap in case of failure of the main or principal ignition points 6 and 7 to function properly.

I further provide an emergency gap capable of operating as an ignition gap in case of failure of the plug to function at either of the gaps previously referred to, said 100 emergency gap being formed between the wire or rod 3 and a wire or rod attached to the metal shell or body of the plug, such emergency ignition gap being shown as formed by the points 22, 23 the first of 105 which is a terminal of the wire or rod 3 and the other a terminal of the rod or wire connected to the metal body and carrying the point 18 already referred to.

In the usual operation of this plug the 110

circuit of the plug is from the leading wire 15 through the artificial gap at points 11, 9 by the wire or rod 4, to and across the main ignition gap, return rod 3, artificial gap at 8, 10, and from the binding nut or post connected to 10, to any return connection (ground or wire).

In the present instance preferably and for the purpose of aiding in the use of other features of my invention, the connection from said binding post is to the post 17 through the removable connection 16 whereby the ignition circuit is completed through the metal shell of the plug and thence by the metal of the engine.

When operating in the normal manner the circuit of the normal ignition gap has two artificial gaps in the circuit thereof whereby the strength of the ignition spark is greatly increased. By observation of the artificial gap at points 8, 10 it can be ascertained whether the main ignition gap is functioning in the normal manner. Should no spark appear thereat and a spark still appear at the gap 9, 11, it will be made apparent that the main ignition is not working but that an ignition spark is being produced at the reserve gap already referred to and directly to the metal shell or other return. In case a spark should not show at either artificial gap the plug may be used in the ordinary way by disconnecting wire 16 and by attaching the lead 15 to the binding post or nut at point 10. The plug would then operate after the manner of the usual single ignition gap plug, the circuit being across the artificial spark gap 10, 8, and across the ignition gap 22, 23 and to ground. The artificial gap at 10, 8 would then be efficacious in increasing the strength of the spark and would also serve to assist in determining whether the plug is functioning properly at its ignition gap.

45 What I claim as my invention is:

1. A spark plug having two artificial breaks or gaps located in the circuit of the ignition gap and respectively at opposite sides thereof.

50 2. A spark plug having an artificial gap located in the ground or return side from the ignition points as and for the purpose described.

3. A spark plug having two artificial gaps located in the circuit of the ignition gap to either side of the latter and in chambers having openings through which the spark of the artificial gaps may be observed.

55 4. A spark plug the integral insulating body or core of which has two conducting wires or rods extending longitudinally therethrough and terminating at one end in points for the ignition gap and at their opposite ends in points for artificial gaps

located in chambers formed in the head of said integral body and provided with observation openings.

5. A spark plug having an artificial spark gap located in a chamber in the head of the plug and wire gauze set in a frame removably fixed in an opening through which the sparking at the artificial gap may be observed.

6. A spark plug having its ignition points at the terminals of lead and return wires insulated in the core of the plug and terminating in the head of the core in points of two artificial spark gaps provided respectively with means for attachment of leading and return wires of the ignition circuit.

7. A spark plug having the points of its ignition gap connected respectively with leading and return wires insulated in the spark plug core and provided with a reserve ignition point located in proximity to a point connected to the leading wire and itself connected to the ground or return.

8. A spark plug having its main ignition gap formed by two points whose connections are insulated in the core of the plug and with a reserve point connected to the metal shell and adapted to function in connection with a point forming the terminal of the insulated leading wire or connection.

9. A spark plug having its main ignition gap formed by two points connected respectively to leading and return wires insulated in the core of the plug and with a reserve point adapted to function in connection with a point forming a terminal of the return wire and itself connected with the metal shell of the plug.

10. A spark plug having a pair of artificial gaps in a circuit of the ignition gap and located in the head of the plug, means for connecting the leading and return wires of the ignition circuit to the outside points of said artificial gaps and means for detachably connecting one of said gaps with the metal shell of the plug.

11. A spark plug having its main ignition gap consisting of points forming terminals respectively of wires insulated in the body of the plug, means for connecting said points respectively with the leading wire of the ignition circuit and with the metal shell of the plug and a reserve ignition point connected with said shell as and for the purpose described.

12. A spark plug having an ignition gap formed at the terminals of wires or connections insulated in the body of the plug, two artificial gaps located in the head of the plug and arranged respectively at opposite sides of the main ignition gap, means for connecting the outside point of one of said artificial gaps with the leading wire of the ignition circuit, means for connecting or

disconnecting at will the outside point of the other artificial gap with the metal shell of the plug and a reserve ignition point connected with the shell directly on the same side of the main ignition gap as the latter artificial gap.

13. A spark plug having its main ignition gap formed at terminals of two wires insulated in the body of the plug, two artificial visible spark gaps in the head of the plug located respectively at opposite sides of the main or ignition gap, binding posts for each of said artificial gaps, a binding post on the shell of the plug and a reserve ignition point connected with the shell and adapted to function with a spark plug point connected to one of said insulated wires.

14. A spark plug having its main ignition gap formed at terminals of two wires

insulated in the body of the plug, two artificial visible spark gaps in the head of the plug located respectively at opposite sides of the main or ignition gap, binding posts for each of said artificial gaps, a binding post on the shell of the plug, a reserve ignition point connected with the shell and adapted to function with a spark plug point connected to one of said insulated wires and a detachable connection between the binding post or terminal of one of the artificial gaps and the binding post or terminal on the shell.

Signed at New York, in the county of New York and State of New York, this 35 13th day of June A. D. 1916.

WILLIAM J. O'GORMAN.
